UNITED STATES PATENT OFFICE

2,583,372

BUILT-IN DECK CHAIR

Phillip L. Hall, New York, N. Y.

Application November 10, 1947, Serial No. 785,014

3 Claims. (Cl. 155—83)

1

My present invention relates to chairs, particularly to deck chairs, and more particularly to an improved built-in deck chair.

The ordinary deck chair, while efficient and useful, is open to a number of serious objections: It is clumsy to handle; it takes up too much storage space on the deck of a boat; it can be used by unauthorized persons; and it requires too much handling to properly service the same.

My present invention is designed to overcome all of the objectionable features of the conventional deck chair. My improved chair, when not in use, is arranged in closed or folded condition each in its own separate casing or cabinet, such cabinets being secured to the side wall of a deck house or the like so as to take up the minimum of deck space, and also being individually locked. This eliminates entirely the necessity of providing a special storage space for the chairs, eliminates handling the chairs, and keeps the chairs in proper position and available for use at all times. Further, by providing locks for the cabinets, unauthorized use of the chairs is prevented, and the personal property of the legitimate holder of the key for such lock, such as books, rugs, cameras, and the like, may be locked with the chair in the cabinet.

An object of my invention is an improved deck chair.

Another object is an improved deck chair of the built-in type.

A further object is a deck chair foldable to a position within an enclosure or cabinet, and in which the bottom of the chair forms the closing panel for the enclosure or cabinet.

A still further object is a deck chair of the built-in type in which the leg rest is slidably mounted in the bottom of the chair, and in which the free end of the leg rest is supported in operative position by means normally housed in the bottom of the chair, and acts as a handle for moving the chair from open to closed position and vice versa.

Other objects and novel features of the construction and arrangement of parts comprising my improved chair will appear as the description of the invention progresses.

In the accompanying drawings illustrating a preferred embodiment of my invention:

Figure 1 is a plan view of the enclosure for the deck chair, and with the chair in extended position;

Figure 2 is generally a side elevation of the structure shown in Fig. 1, but with the enclosure for the deck chair shown at its top end in a section taken on the line 2—2 of Fig. 1;

Figure 2a is a sectional plan view, taken on the line 2a—2a of Fig. 2, and looking in the direction of the arrows;

Figure 3 is a sectional elevation, taken on the

line 3—3 of Fig. 1, and looking in the direction of the arrows.

Figure 3a is a sectional plan view, taken on the line 3a—3a of Fig. 3, and looking in the direction of the arrows;

Figure 3b is a sectional plan view, taken on the line 3b—3b of Fig. 3, and looking in the direction of the arrows;

Figure 3c is a sectional elevation, taken on the line 3c—3c of Fig. 3, and looking in the direction of the arrows;

Figure 4 is a sectional elevation, taken on the line 4—4 of Fig. 1, and looking in the direction of the arrows;

Figure 4a is a section, taken on the line 4a—4a of Fig. 4, and looking in the direction of the arrows;

Figure 4b is a vertical section, taken on the line 4b—4b of Fig. 4, and looking in the direction of the arrows;

Figure 5 is a vertical section taken on the line 5—5 of Fig. 3, and showing the deck chair operating and locking mechanism in rear elevation;

Figure 5a is a sectional view, taken on the line 5a—5a of Fig. 5;

Figure 5b is a sectional elevation, taken on the line 5b—5b of Fig. 5;

Figure 5c is a section view, taken on the line 5c—5c of Fig. 5.

Figure 6 is a plan view, partly in section, and taken on the line 6—6 of Fig. 4; and

Figure 7 is a perspective view showing a plurality of deck chairs embodying the invention, together with their enclosing casings, such casings being arranged along the side wall of a deck house, and with the respective chairs in varying conditions of operation, from full closed to full open.

Referring to the drawings, there is shown in Fig. 1 a plan view, in Figs. 2 and 3 a sectional side elevation, and in Fig. 7 a perspective view of a casing or cabinet 10 into which my improved deck chair is built and housed. A plurality of these casings or cabinets 10 are secured to the outer side wall of the usual deck house or other enclosure bulkhead 11 of a boat in any desired manner. The lower front edge of the enclosure or cabinet 10 is raised above the deck 12, as is the entire bottom of the cabinets 10 to permit swabbing thereunder, and on such lower front edge is secured a hinge 13. Secured to hinge 13 is the lower edge of a metal plate 14, which constitutes not only a closure for the cabinet 10, but also is the bottom member of the seat of the chair comprising my invention.

Mounted on and secured to the upper rear end of the bottom member 14 of the chair and extending from the rear end forwardly, and arranged parallel to and spaced apart from each other and

from the sides are brackets 15. Lying parallel to and against the inner faces of the brackets 15, and secured to the bottom member 14 are reinforcement members 16. Reinforcement members 16 extend forwardly to the front of the bottom member 14. Fastened to the inner face of reinforcement members 16 and spaced above the bottom member 14 are angle members 17 lying parallel to the bottom member. On the upper face of the bottom member 14 at the rear of the angle members 17 and extending between said angle members 17 is a Z bar 18. Also at the front end is a Z bar 19 on the top of which is a channel bar 20. Also secured to the upper face of the bottom member 14 parallel to and spaced apart from the angle members 17 are Z bars 21 of the same height as the Z bars 18. This construction provides an open platform on which rests a seat 22 preferably composed of foam rubber or equivalent cushioning material.

A slideway 23 is provided at each end of channel bar 20 in which slide the ends of a rod 24 secured to the inner face of a leg rest 25, and which acts as a means for preventing such leg rest from being entirely withdrawn from attachment to the seat structure. A Z-bar 19 is provided across the entire front margin of the bottom 14 and is bored to provide a slideway for the rods 26 just outboard of Z-bars 21. The rods 26 have formed integral therewith at their outer ends the downwardly extending U-shaped member 27. The member 27 acts as a support for the outer end of the leg rest 25 and also as a handle means for manipulating the chair to move the elements thereof into and out of the casing or cabinet 10.

Pivotedly mounted at a point above their lower ends on the brackets 15, by bolts 28 and nuts 29, are the side members 30 of the back of the chair. Appropriate cross members, such as the members 31, hold the side members 30 in proper operative relation. Secured to the outer face of the side members 30, by welding, riveting, or in any other suitable manner, are the gussets 32, to which are pivotedly mounted, by bolts 33 and nuts 34, the rear ends of the arms 35. These arms are preferably built hollow, and are substantially rectangular in cross section, as viewed in Figs. 4a and 4b, and at the rear end thereof, there is in each a spacing bushing 36 through which the pivot bolts 33 pass. Secured to the upper face of the arms 35, as by the screws 37, are arm pads 38, such pads preferably being made from foam rubber or equivalent cushioning material. The forward ends of the arm pads fall short of reaching the front end of the arms 35, and I have arranged, in the exposed top face of the forward ends of these arms, the sunken ash trays 39.

Secured to the inner face of each of the arms 35 intermediate the ends thereof and extending downwardly therefrom are the gussets 40. Pivotedly attached to each of the gussets, by bolts 41 and nuts 42, is the upper end of a link 43, the lower end of which is pivotedly attached to the reinforcement members 16 by bolts 44 and nuts 45.

Secured to the inner surface of the side members 30 adjacent to but below the top ends thereof are the angle members 46 (see Figs. 3 and 3a). Slidably mounted on the members 46 are the rectangular members 47, joined together by the crossplate 48. The members 47 and 48 are jointed together at their top end by a plate 49 provided with an eye 50. Secured to the lower face of the plate 49 is a hinge 51 and to this hinge is secured an angle member 52 which carries a head

rest 53. The space between the rear of the head rest 53, the plate 48, and the side members 30 forms a compartment 54 for holding books, gloves, etc. Access to compartment 54 is obtained by swinging the head rest 53 upwardly about the hinge 51 as a pivot.

Referring now to Figs. 3, 3b and 3c, the back is comprised of an angle iron frame plate 55 on which is secured cushion back 56 of foam rubber or the like. Secured to flanges of frame 55 and extending longitudinally thereof are slideways 57 through a wall of which is provided a lip 58. Slidable in slideway 57, is a member 59 provided with a vertical groove 60. Secured to member 59 is the lower end of a friction spring 61, the upper end of which is free and passes through the vertical groove 60 so as to bring the upper end into position to engage with the blister 58. When the members 59 of the back rest are positioned in the slideways 57 and the back rest lowered to the position shown in Figs. 3 and 3c, the free end of the friction spring snaps under the blister 58 and removably maintains the back rest 56 in position on the side frame members 30.

The upper ends of the side frame members 30 are pivotally attached to the lower end of the links 62 by bolt 63 and nut 64. The upper end of each link 62 is pivotally mounted on a member 65 secured to the side plates of the casing or cabinet 10.

The upper end of the front of the cabinet 10 is closed by a plate 66, the lower edge of which lies flush with the forward edge of the seat bottom member 14 when the apparatus is in closed position. Formed on such lower edge of the plate 66 is a guide lip 67.

Referring to Figs. 5, 5a, 5b, and 5c, there is shown a housing 68 secured to the inner face of the plate 66, as by spot welding, and also below said plate parallel thereto and adjacent the lower edge of the plate 66 is a transverse bar 69. Secured to the Z bar 19 on the forward edge of the chair bottom 14 is a transversely extending double layer bar 70, adapted to be engaged by locking bolts 71 that are slidably mounted in the transverse bar 69.

Centrally arranged in the plate 66 is a hole in which is secured an escutcheon plate 72. In alignment with the escutcheon member 72, and in the housing 68, is a stud 73. This stud 73 projects into the escutcheon plate 72 and the projecting end has a non-circular portion 74 and a circular enlargement 75 thereon. The body of the stud 73 is rotatably mounted in a bearing formed in the escutcheon member 72 and housing 68. The end of the stud 73 adjacent the body thereof is reduced in diameter and threaded to receive a nut 76. On the reduced portion is mounted a double cam member 76 provided on either end thereof and below the center of rotation with cam rollers 77. Fitting into the escutcheon member 72 is a key 78, the inner end of which is provided with a non-circular hole 79 which fits onto the non-circular portion 74 of the stud 73, and by means of which stud 73 is rotated.

Secured to the housing 68, and on each side of the stud 73, are straps 80, and 81, spaced from and lying parallel to the housing. Passing through each strap 80 and the housing is a shaft 81. On each of the shafts 81 is rotatably mounted a bar 82, intermediate their ends. The inner ends of the bars 82 are pivotally attached together by a shaft 83. The outer ends of the bars 82 are pivotally attached to the upper ends of

the locking bolts 71. On the housing 68, adjacent to the outer ends of the bars 82, are housings 84 for maintaining such bars in proper alignments. Secured, one end to the housing 68, and the other end to one of the bars 82, is a coil spring 85, which tends at all times to urge the locking bolts 71 into locking position.

The bars 82 are rotated to remove the locking bolts 71 from engagement with the locking bar 70 on the Z bar 19, and this regardless of the direction of rotation of the double cam 76. Either one of the cams 77 will rotate the bars 82 in the proper direction to unlock the locking bars 71.

In operation, and assuming that it is desired to open the chair to its fullest extent, the operator, by utilizing the key 78, as shown in Fig. 5b, operates the double cam 76 so as to move the locking bars 71 from engagement with the locking plate 70. He will at the same time, grasp the U-shaped member 27 and pull the same outwardly from the cabinet 10, as is indicated at the partly open unit at the left of Fig. 7. By continued pulling on the U-shaped member 27, the chair is fully opened as shown in the next to the right chair in Fig. 7.

In the chair referred to, the head rest 53 is shown rotated on the hinge 51, so as to afford access to the compartment 54. After the chair is fully opened, the operator may use the chair in that condition, that is, without using the leg rest 25, or, if he desires to use the leg rest, he may pull on the U-shaped member 27, thus pulling out the rods 26 to the position shown in the fully opened chair at the right in Fig. 7. When the U-shaped member 27 is in its extended position, the operator will pull the leg rest 25 outwardly from its housing under the seat 22 and let the outer end rest on the bar 27.

To close the chair and house the same in the cabinet 10, the operator reverses the operation just described. The leg rest 25 is pushed back under the seat 22. The bar 27 is pushed to slide the rods into position in the seat frame. The bar 27 is then lifted so as to rotate the chair bottom 14 about the hinge 13, as a pivot, thus moving the side members 30 of the back upwardly, and into the dash line position shown in Fig. 2. Continued rotative movement of the chair bottom 14 about the hinge 13 will cause the elements of the chair to fold into a compact mass within the cabinet 10, as indicated by the dash lines in Fig. 2. When the chair bottom reaches the position with its upper edge about to ride flush with the surface of the plate 66, the locking bar 70 (see Fig. 5a) will engage with the bevelled end of the locking bolts 71, moving the same upwardly sufficiently to permit passage of the bolt 71 over the locking bar 70 and into the position shown in Fig. 5a, whereupon the spring 85 will rotate the bars 82 to move the locking bars 71 into the locking position with respect to the locking bar, as shown in Figs. 5 and 5a.

While I have described and illustrated my invention as a built-in deck chair, it will be understood that such treatment is illustrative and not limiting and that the principles of my invention may be applied to various other installations of foldable chairs.

It is also to be understood that since many changes in the construction and arrangement of parts comprising my improved chair may be made without departing from the spirit of the invention, I do not therefore, limit myself to the

exact structure shown and described, other than as set out in the appended claims.

Having thus described my invention, what I claim as new is:

5 1. An improved built in deck chair comprising a flat cabinet secured to a bulkhead, a door for said cabinet hinged at its lower margin to the cabinet to let down in a substantially horizontal plane, a chair seat secured to said door on its inner surface, brackets secured to said door flanking the said seat and providing the door with longitudinal rigidity, a chair back, links connecting the upper end of the said back within the upper end of said cabinet, the lower end of the chair back pivotally connected to the said brackets at a point substantially up from the hinge of the door, and the links positioned and adapted to retain the back against further downward movement when the said door is lowered to a substantially horizontal position whereby the said back serves as a strut to hold the chair seat in position.

10 2. An improved built in chair comprising a cabinet secured to a bulkhead, a door for the cabinet, a hinge connecting the door to the cabinet at the lower margin of the door, a chair seat mounted on the inner surface of the door, a chair back pivotally connected at its lower end to the said door at a point between half way up the door from the hinge and one quarter of the way up from the said hinge, links pivotally connected at one of their ends to the cabinet inside and above the level of the said door, and at their other ends connected to the said back, whereby the door may be lowered to bring the said back down into a reclining position, with the links retaining the back against further downward movement and thereby holding the door and seat up, and whereby the door may be elevated to a closed position with the links pivoting inside the cabinet and the back housing itself therein.

15 3. An improved built in deck chair comprising a cabinet secured to a bulkhead, a door for the cabinet hinged along the lower margin thereof to swing down into a substantially horizontal position; a chair seat mounted on the inner surface of the said door, means retaining the said door in substantially horizontal attitude comprising a chair back pivotally connected to the door at a point up from the hinged connection thereof to the cabinet, and links pivotally connected to the upper end of the said chair back, and to the inside of the cabinet, the said links adapted to retain the said back against downward motion when the door and seat are in a substantially horizontal position and likewise adapted to pivot and allow the upper end of the said back to rise upward within the cabinet when the said door is raised and closed.

40 PHILLIP L. HALL.
